(57) **CLAIM**

The ornamental design for a kid's camera, as shown and described.

DESCRIPTION

FIG. 1 is a top, front and right side perspective view of a kid's camera showing my new design;

FIG. 2 is a top, back and left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a top, front and right side perspective view thereof, shown with the display in an opened configuration; and,

FIG. 10 is an enlarged view of portion 10 shown in FIG. 2. The broken lines depict portions of the kid's camera in which the design is embodied that form no part of the claimed design. The dot-dash broken lines encircling an enlargement portion of the design forms no part of the claimed design.
